DESIGN FOR A NAPKIN HOLDER OR THE LIKE

Bernard Ulvad, Leominster, Mass., assignor, by mesne assignments, to Foster Grant Co., Inc., Leominster, Mass., a corporation of Massachu-
sets

Application March 27, 1948, Serial No. 145,398

Term of patent 14 years

(Cl. D44—24)

To all whom it may concern:

Be it known that I, Bernard Ulvad, a citizen of the United States, residing at Leominster, in the county of Worcester, State of Massachusetts, have invented a new, original, and ornamental Design for a Napkin Holder or the like, of which the following is a specification, reference being had to the accompanying drawings, forming part thereof, in which:

Figure 1 is a side elevational view of a napkin holder or the like, showing my new design; and

Fig. 2 is an end elevational view thereof.

I claim:

The ornamental design for a napkin holder or the like, substantially as shown.

BERNARD ULVAD.
